United States Patent Office.

WARREN SHUMARD, ARTHUR LYON, AND JASPER N. ROBBINS, OF GOSHEN,
OHIO.

Letters Patent No. 63,658, dated April 9, 1867.

IMPROVEMENT IN SAW-MILLS.

The Schedule referred to in these Letters Patent and making part of the same.

TO WHOM IT MAY CONCERN:

Be it known that we, WARREN SHUMARD, ARTHUR LYON, and JASPER N. ROBBINS, all of Goshen, in the county of Clermont, and State of Ohio, have invented a new and useful Scroll-Saw; and we hereby declare the following to be a full, clear, and exact description thereof, reference being had to the accompanying drawings, making a part of this specification.

This is an improvement in the class of scroll or jig-saws adapted for getting out wheel felloes, and other circular objects; and our invention relates more particularly to an arrangement of mechanism by which the upper stroke of the sash is made effective for feeding the stuff.

Figure 1 is a perspective view of a machine embodying our invention.

Figure 2 is a transverse section thereof.

A is a bench, to which is pivoted a rest, B, having a segmental head, C, upon which the stuff rests. The rest B is slotted, b, for the traverse of a bolt, D, having a nut, E, by which a jaw, F, is held to any desired distance from the centre or pivot-bolt. The parts D E F constitute a clamp for holding the stuff down firmly upon the rest during the operation of sawing. The rest B is armed with a segmental ratchet, G, by which the rest is intermittently advanced by an instrumentality to be presently explained. H is a customary sash, armed with a scroll-saw, I, reciprocated by pitman J in the usual way, and guided in a frame, K, from whose upper portion depends an arm, L, which, extending obliquely forward and resting by its extremity on the stuff, effectually prevents any retrograde motion thereof.

The rest is fed intermittently forward by the following contrivance: M is a bar, whose upper end is pivoted to the upper part of the sash, and whose lower end has a screw-threaded aperture which engages upon a screw, N, whose point is secured in a socket, O, in the lower part of the sash, and by which the bar can be set more or less oblique from the path of the sash. Grasping the bar M is a lever, P, provided with a pawl, Q, having a spring, R, that holds said pawl constantly in gear with the segmental rack G. The effect of this arrangement is that on the descent of effective stroke of the sash to retract the pawl, and on the ascent, or non-effective stroke of the sash, to advance the pawl, and the rack-rest also. By setting the bar outward a more rapid feed is obtained, and the reverse by setting it in a more vertical position. The same machine is made applicable for any size of felloe by applying a rest of appropriate dimensions.

We claim herein as new, and of our invention—

The arrangement of oblique adjustable bar M on the sash H, in combination with the screw N, lever P, pawl Q, and segmental rack G, for the automatic feed of the rest B, in the manner set forth.

In testimony of which invention we hereunto set our hand.

WARREN SHUMARD,
ARTHUR LYON,
JASPER N. ROBBINS.
